UNITED STATES PATENT OFFICE.

LUDOLF H. DE WYK, OF GRAND RAPIDS TOWNSHIP, KENT COUNTY, MICHIGAN.

LIFE-SAVING APPARATUS.

1,152,305.

Specification of Letters Patent. Patented Aug. 31, 1915.

Application filed August 15, 1910. Serial No. 577,278.

To all whom it may concern:

Be it known that I, LUDOLF H. DE WYK, a subject of the Queen of the Netherlands, and resident of the township of Grand Rapids, in the county of Kent and State of Michigan, have invented new and useful Improvements in Life-Saving Apparatus, of which the following is a specification.

When submarine, or other boats, sink, or, for any cause, cannot be raised to the surface of the water, the crew imprisoned therein sometimes suffocate, not by drowning, but for lack of respirable air.

The object of my present invention is to provide an improved, simple and effective life-saving apparatus whereby such crew may escape. This object is attained by, and my present invention is embodied in, the mechanism hereinafter described, illustrated by the accompanying drawings, in which—

Figure 1 is a side elevation of my life-saving apparatus: Fig. 2 is a vertical section of the same on line 2—2 of Fig. 1, the life-saving vessel not being shown, and certain parts not being sectioned: Fig. 3 is a like view of the same on a line corresponding with line 3—3 of Fig. 2: Fig. 4 is a horizontal section of the same on a line corresponding with line 4—4 of Fig. 2: Fig. 5 is a section of the chamber for containing the life-saving vessel, on a line corresponding with line 5—5 of Fig. 3: Fig. 6 is an enlarged fragmentary view, in vertical section, of the parts shown at the upper left-hand corner of Fig. 3; Fig. 7 is a side elevation of the life-saving vessel: Fig. 8 is a vertical central section of the same: Fig. 9 is a like view of the lower or body part of the same, sectioned on a line corresponding with line 9—9 of Fig. 8, and illustrating also the position of a man therein, the adjustment of his breathing apparatus, etc., certain parts being omitted: Fig. 10 is a horizontal section of the life-saving vessel on line 10—10 of Fig. 7: Fig. 11 is a like section of the same on a line corresponding with line 11—11 of Fig. 9: Fig. 12 is an enlarged vertical section of the bottom part of the same on line 12—12 of Fig. 11: Fig. 13 is a fragmentary enlarged view of parts of the frame-work of the life-saving vessel: Fig. 14 is a detail view of another part of the same: Fig. 15 is a detail view of the same parts shown in Fig. 14 as seen from another direction: Fig. 16 is a fragmentary view showing in detail the connection be-

tween the two separable parts—the body and the cover—of said vessel: Fig. 17 is a sectional view of the same on line 17—17 of Fig. 16: Fig. 18 is an enlarged vertical sectional view of the topmost part of the cover of said vessel, certain parts not being sectioned: Fig. 19 is a fragmentary enlarged view showing in vertical section a portion of the cover of said vessel, illustrating the construction of its frame-work: Fig. 20 is a transverse section of the same on line 20—20 of Fig. 19: Fig. 21 is a fragmentary view of the connection of the parts of the frame-work shown in Fig. 19: Fig. 22 is a detail, enlarged face view of the means for tightly closing the door of the chamber 1: Fig. 23 is a side view of the same, and Fig. 24 is a detail view of part of the same.

I provide a boat with a water-tight, air-tight chamber adapted to be opened to admit from the interior of the boat and to discharge to the exterior of the boat, a similarly tight vessel adapted to contain a man and to float with him to the surface of the water. This chamber may have a port, or opening, from the interior of the boat through which such vessel may be placed in the chamber, and a second port or opening through which said vessel may pass out into the water, such ports being provided with covers for tightly closing them.

A preferable form of construction of such apparatus and operating devices is shown in the drawings. Reference being had thereto, the air-tight and water-tight chamber 1, cylindrical in shape, has an opening through the outer wall or deck 2 of the boat, and another opening into the boat's interior. These openings respectively may be tightly closed and opened by their covers 3 and 4. The cover 3 is hinged at 5 and may be swung to open or to close it, as by the piston 6 having a connecting link 7 and reciprocating in a cylinder 8, to which air may be admitted through the cock 105, and to which compressed air may be supplied, or from which air may be exhausted, in any suitable manner through the pipe 9 having a suitable valve-cock 10. The cover 3 is tightly held in its closed position by the screw-bolt 13 passing through an opening in the deck, and having a hook portion 14 to engage said cover, and a nut 15 and a square extremity 16, inside the boat, by which the bolt is operated to hold or release the cover. The cover, or door, 4, semi-circular in transverse

section, is hinged at 11 to the walls 12 of the chamber 1 and may be provided with strengthening bands 115. It is tightly held in its closed position by latches, each comprising a swinging arm 17 weighted at 18 and pivoted at 19 on the wall 12, and a hook 20, spring-pressed at 21, pivoted at 22 on the arm 17 and adapted to engage a keeper-lug 23 on the door 4. By reference to Fig. 22, which shows the latch raised in its inoperative position and the door not quite closed, it will be seen that, by the action of closing the door entirely, the striker 24 on the door will strike the weight 18 and tilt it far enough beyond its center of gravity to allow it to fall and carry the arm 17 to its horizontal position; and that, as the arm is thus falling, the hook 20 will engage the lug 23 under the pressure of the spring 21; also that, after such engagement, the action of the further fall of the weight is to more tightly close the door, or to clamp it in its closed position, owing to the location of the pivots 19 and 22 relatively to the lug 23. The door 4 may thus be closed by one inside the chamber, by his merely drawing it shut after him.

One or more (two in the construction shown) side passages 25, having air-tight, water-tight, walls 31, are provided, each leading from an opening through the wall or deck of the boat to the chamber 1. This opening is closed, as desired, by a suitable cover, as the double doors 26 hinged to the deck at 27 and swung by a shaft 33 rotatable as hereinafter described, journaled in a strut 32 and a bearing block 116, and having a threaded portion 28 on which travels a nut 29 connected by links 30 to the halves of the cover.

A suitable life-saving vessel 34, buoyant and air- and water-tight, adapted to contain a man and to float with him to the water's surface, may be placed in the chamber 1 through the opening having the door 4, and may pass out of said chamber through the opening having the cover 3. This vessel may be constructed of any material which is suitable and sufficient to exclude water and to withstand the pressure: in the construction shown the vessel is of waterproof canvas or other suitable fabric, and supported by sufficient framework. The lowermost portion 35, however, is of sheet metal and has a downwardly-extending rim 36 adapted to fit into the corresponding annular recess 37 in the bottom of the chamber 1 to more securely seat the vessel therein. To an upwardly-extending rim 38 of such lowermost part 35 is attached, as by bolts 39, the base rim 40 of the framework, which framework comprises vertical supports 41 and 42, circularly arranged and pivoted on the base rim 40, on parallel circular ribs 43 and on the top interior rim 48. By the

pivotal connections 44 between these supports 41 and 42, and by arranging at each such pivotal connection a suitable spring-pressed catch 45 on one support 41, adapted to engage a pit 46 in the other support 42, the canvas vessel may be partially collapsed and may be extended to its full size and shape as desired. The vessel's top or cover portion 47 may be removed to admit its occupant and then replaced by himself. The cylindrical part of this cover is composed of material similar to the body of the vessel and has a framework comprising supports 49 pivoted at 90 on the interior base rim 91 of the cover, and detachably carrying in a suitable retaining recess 50 a circular rib 51. The uppermost portion 92 of the cover is conical and of sheet metal, and may be provided with a small glazed window 98. In guides 93 in ribs 94 of this cone travel the lugs 95 at the upper ends of the supports 49 shouldered at 96 to receive the top rim 97 of the cylindrical part of the cover. It will be seen that by moving these supports 49 upward on the guides 93 the cylindrical part of the cover may telescope inside the cone 92. This cone has an opening 102 at the top, which is tightly closed by a corresponding hollow, conical metal cover 99 which is moved to open or close such opening by the screw 100, having an operating hand-wheel 101, as shown in Fig. 18. A suitable rubber buffer 103 at the top of this cover 99 is adapted to press against the inside of the door 3, as the chamber 1 fills with water, and the vessel 34 is raised thereby, as hereinafter explained. The cover 47 may be tightly secured in place by lever latches 52, circularly arranged around the base rim 57 of the cover, each fulcrumed thereto at 56 and having a hook 53 pivoted thereto at 54: when the hook 53 has engaged and holds the upper rim 58 of the body of the vessel, the handle portion 59 of the latch is then turned to the position shown in Fig. 17, whereby the cover is tightly and securely held in place.

The main portion of the body of the vessel 34 is provided with a collapsible air chamber 60, as of rubber, which may be inflated to impart sufficient buoyancy to the vessel to float its load, even if the vessel should fill with water when the surface has been reached and the cover removed.

In the bottom portion 35 of the vessel are contained an oxygen tank 61, air cooler 62, and air purifier 63, all of any approved form and construction. The occupant, as shown in Fig. 9, has attached to his nose and mouth the breathing apparatus comprising tubes 64 and 65, one for inhaling and the other for exhaling. These lead from a breathing bag or chamber 66 to which oxygen may be supplied from the tank 61 through the tube 67, which is joined

by the tube 68 leading from the cooler 62, the expired air passing through the tube 69 to the purifier 63, whence it passes by the pipe 70 to the cooler: these tubes above the base portion 35 being of rubber or other flexible material.

My life-saving apparatus is operated in the following manner: The covers 3 and 26 are tightly closed at all times save when it is necessary to make use of my apparatus. Supposing the ship to be sunken, the bolt 18 holding the cover 3 is loosened: a collapsed life-saving vessel 34 is placed in the chamber 1; one of the crew enters the vessel, 15 straightens the supports 41 and 42 to expand the vessel to its normal shape, inflates the air chamber 60, adjusts his breathing apparatus, closes the door 4 of the chamber 1, and tightly secures the cover 47 of the vessel in place. Cocks 71 in the waste pipes 72 are closed. The crew in the vessel then turn the crank 73, rotating its shaft and gearing 74, which meshes with the gear 75 on the shaft carrying the gears 76 and 77. 20 The gear 76 meshes with the gear 78 on the shaft carrying the gear 79. The gears 77 and 79 respectively mesh with the gears 80 and 81 which turn the gears 82 and 83 on their shafts respectively. These in turn 25 mesh with the gears 84 and 85 on the shafts 33. Thus these shafts are turned to draw the nuts 29 inwardly to open the covers 26. Water now pours in and fills the chamber 1 (except the space occupied by the vessel 34), 30 the side passages 25 and the open space connecting and below them. This done, the cover 3 is raised as by exhausting the air from the cylinder 8. Thereupon, the vessel 34 floats out of the chamber and to the surface 35 of the water. The covers 26 are now closed by turning the crank 73 and the cover 3 is closed by admitting air into the cylinder 8 through the cock 105, and compressed air may be supplied from a suitable source 40 by opening the cock 10. The cocks 71 are now opened, and the water contained in the chamber 1, side passages 25, etc., runs out of the waste pipes 72 into the hold of the vessel, air being admitted from the cocks 45 106 and 107. Thereupon, the cocks 71, 107 and 106 are closed, another vessel 34 placed in the chamber 1, and the operation is repeated, whereby its occupant escapes. This is continued until only one man remains. 50 He opens the cock 105 that the piston 6 may readily descend when water fills the chamber 1: he adjusts another vessel 34 in the chamber in such position that the squared recess 108 of the shaft 110 carried in the base of the vessel fits on the squared end 55 109 of the shaft 111, rotatable in bearings carried by the walls of the chamber and passages, as shown. Adjusting the cover 47 and other apparatus, as hereinbefore explained, he next turns, as by any suitable

wrench fitted on its squared end 112, the shaft 110, which action rotates the shaft 111 with its gear 113 meshing with the gear 114, whereby the gears 76 and 78 are turned to open the covers 26, as explained. Water 70 now enters, the vessel 34 floats, and its top pressing against the cover 3, swings it open, it being balanced to turn easily.

It is manifest that my invention may be embodied in other and varying forms without departing from its essence.

Not confining myself therefore to the details of construction shown and described, I claim:—

1. In an apparatus of the character described, a water-tight and air-tight vessel adapted to contain a man and to float with him to the surface of the water, and a boat having a similarly tight chamber and provided with means operable from the boat's interior to open and close the chamber to admit said vessel from the interior of the boat and to permit the passage of the same to the exterior of the boat, said boat being provided with a similarly tight side passage leading from the boat's exterior to the chamber, and having means operable from within the boat for tightly closing and opening said passage.

2. In an apparatus of the character described, a life-saving vessel having a cover with a conical upper portion and a cylindrical lower portion, said lower portion being collapsible and having a frame-work comprising supports adapted to be slid in guides in the conical portion.

3. In an apparatus of the character described, a life-saving vessel having a conical top portion with an air passage therethrough, a corresponding conical cover for said passage and means for tightly clamping the cover on said conical portion to close the passage.

4. In an apparatus of the character described, a water-tight and air-tight vessel adapted to contain a man with air for his breathing and to float with him to the surface of the water, a boat having a similarly tight chamber and provided with means operable from the boat's interior to open and close the chamber to admit said vessel from the interior of the boat and to open said chamber to the exterior of the boat to permit the passage of said vessel to the boat's exterior, and means operable from the interior of the vessel to open the chamber to admit water to float the vessel.

5. In apparatus of the character described, a boat having a tight chamber closable and openable to the boat's interior and also to the boat's exterior, and a buoyant and air-containing vessel adapted to contain a man and float him to the water's surface and to supply him with breathing air meanwhile and adapted to be inserted into the chamber.

from the boat's interior and to pass out of the chamber into the water exterior to the boat, and having means extending through its wall for opening the chamber to the boat's exterior and operable from within the vessel.

In testimony whereof I have hereunto set

my hand in presence of two subscribing witnesses.

LUDOLF H. DE WYK.
